UNITED STATES PATENT OFFICE.

FREDERICK F. BISCHOFF, OF CHICAGO, ILLINOIS.

DESIGN FOR A PANEL FOR CEILINGS, &c.

SPECIFICATION forming part of Design No. 20,502, dated February 3, 1891.

Application filed October 20, 1890. Serial No. 368,729. Term of patent 14 years.

To all whom it may concern:

Be it known that I, FREDERICK F. BISCHOFF, a citizen of the United States of America, residing at Chicago, in the county of Cook and State of Illinois, have invented and produced a certain new and original Design for the Embossed Margin of Sheet-Metal Panels for Ceilings, &c., of which the following is a specification, reference being had therein to the accompanying drawing.

The drawing accompanying this specification conveys to any one skilled in the art of sheet-metal working a clear understanding of the said design and is sufficient to enable such person to use my invention.

The figure is a face view of the panel mounted or set upon a background of any suitable material.

A is the background.

B is the panel, which has a raised ridge *b* 20 around the edge, provided with suitable ornamentation—as, for instance, beads, as shown—and raised work *a*, of suitable ornamental configuration, formed on the body of panel.

I claim—

A design for sheet-metal panels, substantially as herein shown and described.

In testimony whereof I affix my signature in presence of two witnesses.

FREDERICK F. BISCHOFF.

Witnesses:

WM. H. LOTZ,
OTTO LUEBKERT.
